DOOR CHECK AND HOLDING DEVICE

Edwin L. Allen, Cleveland Heights, Ohio, assignor
to Rudolph I. Schonitzer, Cleveland, Ohio

Application April 13, 1948, Serial No. 20,680

1 Claim. (Cl. 16—86)

1

This invention relates to a combination check and holding device for retaining in a predetermined position with respect to each other two cooperating members such as an automobile door and its frame and more particularly to a device for checking the movement of a door or the like in one direction and then retaining the door in the checked position.

The subject matter of this invention is particularly adapted for use in conjunction with doors and door frames of automobiles and the like in which the door is hinged on an axis that is approximately vertical and is swung between opened and closed positions about that axis. The doors of automobiles now built frequently are hingeably mounted on inclined body posts or pillars in such manner that they have a natural tendency to swing to a closed position and this tendency has resulted in serious personal injury, creating a requirement for means for releasably holding such doors in open position whenever they are moved thereto. The present checking and holding device functions resiliently to limit the amount which the door may open and thereafter to retain the door in that position until it is pushed manually to another position. More specifically the invention relates to the combination of a link member, one or more spring arm camming elements carried thereby and the elements by which the link and cam members are secured together in operative relation; and as such represents an improvement over the device disclosed in Patent No. 2,237,046, issued April 1, 1941 to A. H. Breitenwischer and now assigned to my assignee.

A general object of the present invention is to provide an improved door checking or door checking and holding mechanism. Another object is to provide a door check including a link with a resilient bumper thereon to limit the extent to which the door may be opened, spring latch mechanism to hold the door open and novel supporting elements to hold the parts together as a unitary assembly and reinforce them in operative position. Still another object is to provide a combination check and holding device including a link carried by either the door or frame with spring arms on opposite faces thereof adapted releasably to engage holding elements carried by the complementary frame or door as the case may be, a resilient bumper or cushion to limit the relative motion of the door and frame, a reinforcing plate to support the cushion and a novel manner of holding the various components in place on the link.

2

Other objects of the invention will become apparent from the following specification and from the drawing; the novel features of the invention being set forth in the accompanying claim.

Referring now to the drawing: Figure 1 is a horizontal section through a portion of a door member and door pillar or post member of an automobile body showing in solid lines the door in closed position and in dot and dash lines the position of the door and door check mechanism in open position; Figure 2 is a section as indicated by the line 2—2 on Figure 1; Figure 3 is an end elevation as indicated by line 3—3 on Figure 1 showing the elements carried by the unsupported end of the mechanism; Figure 4 is a fragmentary view similar to Figure 1 showing a modified form of checking and holding mechanism; Figure 5 is a section through Figure 4 as indicated by the line 5—5 thereon; and, Figure 6 is an end elevation of the mechanism shown in Figure 4.

As indicated above, the drawing illustrates two forms of the invention, both of which have certain common characteristics. Each form includes a link member of a door check and holding mechanism together with at least one spring arm held against a broad face of the link. A deformable cushion surrounds the link and spring arm and operates to cushion relative motion of the door and frame in one direction; and is supported by a plate or disc that likewise surrounds the link and spring arm. A fastening device holds the link and spring arm together and provides an abutment against which the plate may bear when a shock or other load applied to the cushion is transmitted to it. Each form of the invention embodies improvements over the Breitenwischer patent described above in that each provides a construction whose components are somewhat simpler to fabricate and require less material, both of which are important factors where the device is used in very large quantities as in the construction of automobiles, where at least two and frequently four check and holding devices are provided on each vehicle.

Referring now to the drawing and particularly to Figure 1, the generally hollow left front door of an automobile is indicated at 10 and is hingeably mounted at 12 to swing about a rearwardly inclined and generally hollow front post or pillar 14 that is rigid with the automobile frame. The inclination of the body posts or pillars causes the door to tend to swing to a closed position so the door shown in Figure 1 in dot and dash lines tends to swing to the closed position shown in 55 solid lines and this can result in serious personal

injury, particularly if such movement of the door is unexpected. The other doors of the car normally are mounted on similarly inclined pillars and hence are subject to the same tendency to close unexpectedly. The door is checked in its opening motion by a resilient shock absorbing cushion or bumper that to a degree cooperates with the spring arm mechanism thereafter to hold the door in the open position. While the particular uses of the door check and holding mechanism described herein are directed toward automobiles, and more particularly to those with inclined pillars, it will be evident that the invention may be used in other circumstances. The constructions described herein represent two preferred forms of the invention and customary method of use but the scope of the invention is limited solely by the appended claim. In the forms of the invention illustrated herein the checking and holding mechanism is shown as principally contained within the hollow door with a link pivotally secured to the door post but it will be evident that the installation may be reversed so the mechanism is largely contained within the hollow vehicle body post or pillar and the link secured to the door.

The present device includes a relatively flat straight stamped steel arm or link 15 having its front end pivotally or otherwise suitably connected to an intermediate portion of the door post 14 as by a bracket 16 secured to the post and pivotally connected with the link by a pin 17 mounted on an axis substantially parallel with the hinge axis 12. The arm 15 lies within the generally hollow door, passing through an opening 19 in the front edge wall 20 thereof and through a thicker vertical reinforcing partition or rib 21 secured as shown to the edge member 20 and the interior panel member 24 of the door. The opening in the edge member 20 is of sufficient size to receive most of the bracket 16 and the pin 17 when the door is in the closed position shown in Figure 1. The opening in the vertical partition 21 is indicated at 25 and is in the form of a slot through which the flat link 15 may pass freely as hereinafter described, the slot being of sufficient vertical width to permit spring arms mounted on the link to pass through the slot when the door is opened or closed. From this description it will be evident, as stated above, that the relative location of the bracket 16 and link 15 may be reversed so the bracket is secured to the door and the link slides into position within the door post.

When the door is in the closed position the check and holding mechanism is inoperative but when the door is opened the mechanism functions first to check the door as it reaches its fully open position and thereafter to hold the door in the opened position until such time as sufficient force is exerted upon it to release the holding mechanism and thereafter push the door to a closed position.

The components that cooperate with link 15 to make up the complete checking and holding mechanism as illustrated in Figures 2 and 3 include two stiff spring arms 30 formed of spring steel and secured in cooperating relation with the link 15 and on opposite sides thereof. While it is preferred that two such spring members be provided it will be evident that, if desired, one only may be used without departing from the present invention. Each spring arm includes a relatively flat portion 33 adapted to lie against the link 15 and a central raised

portion 34 providing a pocket between the link and the arm. The arm is bent inwardly at 37 again to contact the link and terminates in an outwardly extending lip 38. The portions 37 and 38 are so shaped that their surfaces adjacent the link act as camming surfaces to raise the spring arm over a bearing part hereafter described and permit the same to become seated and releasably locked in the pocket or removed therefrom. Each spring arm is secured permanently to the link 15 by a rivet 40 that passes through each arm and the link as shown.

In order to absorb the shock incident to stopping the motion of the door when it reaches the open position a cushion 41 is mounted on the link as shown in Figure 2. This cushion is in the form of a resilient pad made of rubber, neoprene or other resilient material; preferably in the form of a relatively thick disc with a central opening to accommodate the link and spring arms. The pad functions as a bumper to cushion a too rapid or forceful opening of the door and also cooperates with the spring arms to limit the amount they may flex outwardly when the door is either opened or closed. When the door is opened, the full amount of the unabsorbed load transmitted by the cushion is taken by a supporting plate or disc 42. This disc is formed to have an area and shape conforming to the adjacent contacting face of the pad and is provided with a central opening permitting it to be mounted in position as shown. The disc is interposed between the pad and rivet so that force transmitted to it by the pad is in turn transmitted to the link through the head 43 and peened over portion 44 of the rivet 40.

The mechanism just described engages with cooperating structure carried by the vertical reinforcing member or partition 21 of the door. This structure is in the form of a boxlike frame 50 riveted or otherwise secured at 51 to the inner face of the partition 21 in position to overlie the opening 25. Two spaced steel bearing parts or arms 53 are supported in the box in such position that they extend across the opening 25 on each side of the link 15 closely adjacent the flat faces thereof.

When the door is swung from closed to open position the various parts move relative to each other from the solid to the dotted line position of Figure 1 during which movement the lips 38 of the spring arms 30 engage the elements 53 and by them are cammed away from the link 15 as the opening motion of the door continues. As the door approaches its final position the portions 37 of the spring arms snap over elements 53 locking them in the pockets formed by the outwardly bowed portions, as shown in dot and dash lines in Figure 1 thereby locking the door in open position.

The force due to the opening motion of the door is absorbed as the door attains the position shown in dotted lines in Figure 1 by the cushion 41 supported by the disc 42. The resilience of the cushion thereafter causes it to exert some inward force on the spring arms so they more tightly hold the elements 53 in the pockets and thus assists in holding the door check mechanism in position. The spring arms 30 are very stiff to insure an adequate grip on the elements 53 although on the other hand the width of the door is such that a relatively small force at the edge of the door multiplied by the moment arm represented by this width enables the door to be closed easily.

When the door is pushed to a closed position the portion 37 of each spring arm acts as a cam surface again to move the adjacent portion away from the link 15 and permit the elements 53 to be withdrawn from beneath the spring arms as the door leaves the dotted line position of Figure 1 to attain the closed position shown in solid lines in that figure.

A modified form of the invention is illustrated in Figures 4, 5 and 6 and differs from the construction described chiefly in the manner in which the spring arms are made and secured to the link 15. In this modified form the various components including the link 15, boxlike frame 50 and the hinged connection of the link at 17 may all be identical with that described in connection with Figures 1, 2 and 3. In like manner the resilient pad or cushion 41 may be of a shape and supported by a disc 42 in all respects as heretofore described.

The two arms 30 shown in Figure 2 are duplicated in Figure 5 but are made up of a single spring member 58 of hairpin like configuration. This member includes two spring arms each having lips 38 and portions 34 and 37 to provide pockets in which the bearing parts 53 may be seated, all as described above. On the other hand these spring arms are joined by an integral piece of material 52 so a single piece of stock provides both spring arm members and by the nature of the construction rigidly secures them in position with respect to each other.

The fact that the two spring arms are made in one piece permits use of a somewhat different method of fastening them to the link 15 than is provided by the rivet 40 as shown in Figure 2. Thus when the spring arms are connected together by the web of material 52 they are held against lateral shifting with respect to each other by the resilience of the web, especially where the web fits snugly against and is supported by the square corners of the end of link 15. It is thus not necessary to hold the arms tightly to the link, as by means of a rivet, to prevent lateral shifting but it is sufficient merely to secure the integrally joined spring arms to the link in proper relation to the end thereof. To this end a cotter pin 55 is passed through two aligned openings in the spring arms and through a corresponding opening in the link 15. The end 52 of member 58 encircles the end of the link 15 and is held as tightly against it as possible so rocking of the spring arms in the plane of Figure 4 is prevented. The legs 51 are spread as shown in Figure 6 and cooperate with the head of the cotter pin to provide a firm support for the disc 42 as the shock of bringing the door to rest against the pad or cushion 41 is imparted to it.

In operation the form of invention shown in Figures 4, 5 and 6 operates precisely as described in connection with Figures 1, 2 and 3 and when the door is moved from the closed to the opened position the lips 38 of the spring arms cam over the bearing parts 53 to seat them in the aforementioned pockets between the link and spring arms. Similarly when the door is closed the spring arms are cammed apart by the surfaces 37 and the door is released to be pushed into the closed position shown in Figure 1.

From the foregoing description it will be evident that I have provided a new and improved form of door check and holding device that possesses the advantage of simplicity of design and of assembly together with a sturdy construction adapted to the conditions incurred by use in automotive vehicles and the like.

I claim:

- 20 A door check and holding device for limiting opening movement of a door member with respect to a supporting frame member and holding said door member in open position comprising, a link adapted to be pivotally connected at one end to one of said members, a pair of independent separate spring arms disposed at the other end of said link and on opposite sides thereof, each of said spring arms being shaped to provide a pocket between the arm and said link adapted to receive keeper elements supported on the other of said members, a resilient cushion element encircling said link and said independent arms intermediate the ends of said arms, a plate member encircling said link and said arms and adapted 25 to engage and restrain said cushion element against movement toward said other end of said link, and a fastening element extending through said spring arms and said link member and having enlarged portions at its opposite ends, said enlarged portions directly engaging said spring arms and directly abutting said plate whereby said spring arms are retained against movement relative to said link and said plate is restrained against movement along said link toward said 30 other end thereof.
